UNITED STATES PATENT OFFICE.

WILFRED R. WOOD, OF DAYTON, OHIO, ASSIGNOR TO THE AMERICAN STOKER COMPANY, OF SAME PLACE.

UNDERFEED STOKER.

SPECIFICATION forming part of Letters Patent No. 608,819, dated August 9, 1898.

Application filed April 29, 1897. Serial No. 634,442. (No model.)

To all whom it may concern:

Be it known that I, WILFRED R. WOOD, a citizen of the United States, residing at Dayton, in the county of Montgomery and State 5 of Ohio, have invented certain new and useful Improvements in Underfeed Stokers, of which the following is a full, clear, and exact description, reference being had to the accompanying drawings, forming part of this 10 specification.

My invention relates to improvements in that class of underfeed stokers in which coal or other fuel is fed continuously into a magazine which is surmounted at the top with 15 twyers for the delivery of air or air and steam at or near the point of combustion, which takes place above the point of delivery of the fuel into the magazine.

The object of my invention is to increase 20 the durability, simplicity of construction, and efficiency of action of this class of stokers, and its novelty will be hereinafter set forth, and specifically pointed out in the claims.

The following is a description of the accompanying drawings, which show my invention embodied in the form at present preferred by me; but it will be understood that various modifications and changes may be made without departing from the spirit of my invention 25 and without exceeding the scope of the claims.

In the accompanying drawings, Figure 1 is a longitudinal sectional view, in side elevation, of a furnace equipped with my improved 30 stoker. Fig. 2 is a plan view of the working parts of the stoker, some of the twyer-blocks being removed and a portion over the motor being broken away. Fig. 3, Sheet 2, is a side elevation of the forward part of the same, 35 partly broken to show the arrangement of the air-controlling devices. Fig. 4, Sheet 2, is an enlarged detail in transverse section, showing the manner of securing the twyer-blocks to the retort or magazine. Fig. 5, 40 Sheet 2, is a broken side elevation looking toward the left of Fig. 4. Fig. 6, Sheet 2, is a sectional detail representing a modification in the construction of Fig. 4. Fig. 7, Sheet 45 3, is a transverse section through the feeding- 50 throat on the dotted line $\alpha\alpha$ of Fig. 8. Fig. 55

8, Sheet 3, is a broken section, in side elevation, on the dotted line $y\gamma$ of Fig. 7. Fig. 9, Sheet 3, is a transverse section on the dotted line 22 of Fig. 10. Fig. 10, Sheet 3, is a side elevation, partly in section, of Fig. 9. Fig. 11, Sheet 3, is a plan view, partly broken, on the dotted line 33 of Fig. 8. Fig. 12, Sheet 4, is an enlarged front elevation of the motor mechanism and adjacent parts. Fig. 13, Sheet 4, is a sectional side elevation of the 60 same. Fig. 14, Sheet 4, is a plan view of the same. Fig. 15, Sheet 4, is a sectional side elevation of the ball-bearing mechanism. Fig. 16, Sheet 4, is an elevation of one-half of the ball-bearing mechanism. Fig. 17 is 65 an enlarged elevation of the actuating-dog.

The same letters of reference are used to indicate identical parts in all the figures.

Referring to Figs. 1 and 2, A is the combustion-chamber of a boiler or other furnace, 70 of which B is the front wall. Set in this furnace with its top about level with the grate surface or floor of the fire-chamber is an oblong trough-shaped magazine or retort C with sloping sides and an upwardly-sloping rear 75 end, and extending forward from the retort through the front wall of the furnace is a tubular conduit D, whose bottom is flush with the bottom of the retort, as seen in Fig. 1, and whose forward end communicates with 80 the lower end of the fuel-hopper E. Journaled axially through the conduit D is a screw conveyer F, which enters the retort C and terminates at a point about two-thirds of the length of said retort, as seen in Fig. 1. 85 This screw conveyer is composed of a polygonal shaft, on which are strung the sections of interlocking flights a, whose hub portions b have bores through them to snugly fit the shaft and conforming to its shape in transverse section. The flights and hub portions within the conduit are of uniform diameter, and the edges of the former closely fit the inner walls of the conduit. From the mouth of the conduit, where it enters the retort C, 90 the hub portions are gradually tapered and enlarged from the front to the rear, as seen in Figs. 1 and 2, so as to gradually reduce the carrying capacity of the flights as they extend toward the rear of the retort; also, if 95 100

desired, the flights themselves may be gradually diminished in diameter as they extend toward the rear of the retort to aid in reducing their carrying capacity.

5 I will now describe the manner of supporting and journaling the screw conveyer, reference being had particularly to Figs. 1, 9, 13, 15, and 16. Suitably secured upon the front of the conduit D is a plate or bearing-piece c, Fig. 13, in which is a vertical socket to receive a pair of washers or bearing-rings d, Figs. 15 and 16, having their adjacent faces annularly grooved to receive and retain bearing-balls e, preferably of chilled steel, and fitted upon 10 the shaft f of the screw conveyer, so as to turn therewith, is a shouldered sleeve g, the enlarged part of which is journaled in and has its bearing in the rear wall of the plate c and the smaller part of which extends through the 15 bores of the ring d and is journaled in the front wall of the plate c. It will thus be seen that the shoulder of the collar g bears against the inner ring and the entire end thrust of the screw conveyer is borne by the balls, the construction forming a very perfect ball-bearing 20 to receive the end thrust. In the wall of the conduit D, Figs. 1 and 9, at the rear end of the conduit, is a semicircular recess in which is removably secured, by means of bolts h, a bearing-plate i, whose inner side conforms to the curvature of the conduit and against which the flights of the conveyer bear at that 25 particular point, thus serving to hold the conveyer down to its work and to a large extent relieving the bearings in the plate c.

30 To actuate the screw conveyer to feed the coal from the hopper E through the conduit D into the retort or magazine C, I employ the following mechanism, particular reference being had to Figs. 12, 13, 14, and 17: Fast on the shaft f in front of the bearing-plate c is a ratchet-wheel j with its hub extended on both sides, on which hub is journaled a two-part sleeve k, each of which parts has secured 35 to it an upwardly-extending arm l and a downwardly-extending arm m. Between the arms m is pivoted a double dog n (see Fig. 17) with two engaging noses o p and with two pivotal bearings q r, preferably connected by 40 a slot s, so that the dog may be instantly shifted from the pin carried by the arms m to cause either the bearing q or the bearing r to engage the ratchet j. For instance, the dog-carrier composed of the parts k m has a 45 constantly vibrating or reciprocating motion imparted to it by any suitable means—in this instance by a well-known form of steam-motor G, whose piston is connected by pivoted links t to the upwardly-extending arms l—and 50 when the nose o engages the ratchet, with the bearing q on the pin of the arms m, as in Fig. 12, the ratchet, together with the screw conveyer, will be turned in such direction as to 55 feed the coal into the retort; but when the dog is shifted to cause the nose p to engage the ratchet, with the bearing r on the pin, the

60 vibration of the dog-carrier will cause an opposite direction of rotation of the ratchet and screw conveyer, which would feed the coal from the retort back into the hopper. This 70 backward rotation of the screw conveyer is sometimes important both to relieve temporary clogging and when it is desired to empty the retort entirely. To insure the proper working of the ratchet-wheel and screw conveyer, so that they may turn continuously and intermittently in one direction, I employ a stop-dog u, Fig. 12, preferably in two parts of unequal lengths and pivoted by a removable pin in a lug v, vertically adjustable on the 75 inner wall of the case surrounding the ratchet. As seen in Fig. 12, there are two of these lugs v one on each side of the ratchet, and when the nose o is in engagement with the ratchet the two-part dog u is on the left; but when the 80 dog n is shifted to bring its nose p into engagement the two-part dog u is likewise shifted to engage the lug v on the right. By these means very nice and perfect adjustments can be made to insure the constant intermitting 85 rotation of the screw conveyer, as will be readily understood.

90 I will now describe the air-blast mechanism for supplying the requisite amount of oxygen to the fuel at or about its zone of combustion, particular reference being had to the figures on Sheets 1, 2, and 3. Surrounding the magazine C and some little distance from it is a jacket or casing H to form a wind-box, entering which and under the conduit D is an 100 air-trunk I, connected to any suitable blast apparatus, the force of the blast being regulated by a gate or valve J, Figs. 1 and 3, pivoted, as at a', and controlled by a lever a² with an operating-handle a³, having a rack 105 engaging a fixed latch-piece a⁴, in this instance on the side of the casing surrounding the ratchet-wheel j. The trunk I and box H form part of the conduit from the blower to the twyer-openings. The top of the magazine 110 C and the top of the jacket H are connected by a horizontal flange b', which, as seen in Fig. 4, may be an extension of the magazine C, or, as seen in Fig. 6, may be an extension of the jacket H, suitable bolts b² being provided to unite them at their point of juncture. The horizontal flange b' is perforated with openings b³, (see particularly Figs. 2 and 5,) and there is seated on the flange twyer-blocks c', which extend upwardly from 115 the flange, so that their inner faces form a substantial continuation of the sides of the retort, though preferably at a slightly-different angle, as shown in Fig. 4. These twyer-blocks are hollow, their lower openings registering 120 with the openings b³ in the flange b', and are provided on their inner faces with suitable outlet-openings c² and on their outer faces along the sides of the magazine and just above the grate level or floor of the fire-chamber with 125 other outlet-openings c³. (See Fig. 4.) These blocks are arranged entirely around the top 130

of the magazine, with their ends abutting to form a continuous wall or wall extension around the top of the magazine. Each of the twyer-blocks is provided with a downwardly-projecting flange c^4 , adapted to fit into one of the openings b^3 , the sides of the flange and the opening being preferably correspondingly tapered, so as to form a close joint to hold the twyer-blocks snugly in position. To secure the twyer-blocks upon the flange and also to permit of their ready removal for repair, replacement, or otherwise, I provide in both ends of each twyer-block, near its bottom, a recessed opening c^5 , having a countersunk portion c^6 to receive one end of a T-headed bolt c^7 , which projects downwardly at an angle through the flange b^3 and through suitable lugs d^8 and is held by a nut on its threaded end. The countersunk portion c^6 of the recessed opening c^5 is provided with a depressed seat c^8 , adapted to receive the projecting ends of the head of the bolt c^7 when the same is turned in line with the sides of the magazine. The construction is such that by loosening the nuts on the bolts and turning them on their axes until the T-heads stand at right angles to the sides of the magazine the twyer-blocks may be raised and removed from the flange or may be replaced thereon, as desired, and by having the bolts extend at an angle through the sides of the air-jacket beneath the grate-surface they may be readily gotten at.

In order to distribute or deflect the air to one side or the other of the magazine, I place in the trunk I a deflector K , which stands vertical in the trunk and is pivoted therein, so as to be moved at different angles, and as a convenient means of operating said deflector its pivot projecting through the trunk is provided with an arm k^1 , connected by a pivoted link k^2 to an operating-lever k^3 , pivoted to the side of the trunk, as shown in Fig. 3.

Secured within the wind-box, preferably to the under side of the magazine, is another stationary deflector L , Fig. 1, to aid in the proper distribution of the air to the twyers.

The fuel-conduit D is provided on its upper side, adjacent to the magazine, with a pocket e^1 , having curved or inclined sides, (see Figs. 1, 2, 7, 8, 9, 10, and 11,) and to this pocket air is supplied by means of a suitable pipe e^2 , which leads around the conduit and communicates with the air-trunk I . A suitable deflector e^3 is placed at one side of the opening to deflect the air into the pipe e^2 , so that a quantity of air is discharged into the conduit in the direction of the feed of the fuel to prevent smoke or gases finding their way back through the conduit and fuel-hopper.

As the retort or magazine C may be subjected to strains liable to crack or break it, either from expansion, contraction, or otherwise, I provide it with one or more transverse sets of adjacent lugs m^1 and between which the metal of the bottom and sides of the magazine is made thinner than the rest of the

body of the magazine. In this instance I have shown two sets of such lugs, which have bolts passed through them, though not tightened up, forming bridges across the lines of diminished resistance, and should any breaking strain occur to the retort it would break or crack between said lugs, and the bolts could then be tightened up to hold the parts securely together without necessitating the removal of the retort and its replacement by a new one, as will be readily understood.

As seen in Fig. 13, all that part of the motor mechanism in front of the hopper E is enclosed by a suitable casing N , preferably constructed with removable sections to give access to the parts, and fitted upon the front end of the shaft k is a cap m^2 , visible through a circular opening in the front of the case N and carrying some distance from its center a piece n^2 , projecting through the opening in the case, which piece is preferably a grease-cup communicating with the bearings within the case, and thus serving the double purpose of a lubricator and an indicator to enable the attendant at all times to see at a glance that the screw conveyer is properly rotated and also in which direction it is rotated.

It will be seen from the above description that I provide a stoker in which the parts are simple and compact with a self-contained motor-driving mechanism. The constructions are such that all parts liable to require repairs are easily and readily accessible. By having the air-chamber completely surrounding the magazine and communicating directly with an air-trunk, which partially surrounds the conveyer, the incoming air prevents the overheating of the conduit or magazine, and at the same time the cooling of the magazine and conduit tends to slightly heat the air which is introduced through the twyers, thus producing a desirable effect both from the standpoint of economy of combustion as well as economy of construction.

Having thus fully described my invention, I claim—

1. In an underfeed stoker, the combination of a retort or magazine, a series of twyer-openings on both sides, said openings being directed across the magazine, a second series of twyer-openings above the floor of the fire-chamber directed away from the magazine, and means for forcing air through said twyer-openings, substantially as described.

2. In an underfeed stoker, the combination of a retort or magazine, a series of openings in the upper part of said magazine discharging toward the interior thereof and additional openings above the floor of the fire-chamber directed away from said magazine, and means for forcing air through said openings, substantially as described.

3. In an underfeed stoker, the combination of a retort or magazine provided with a series of twyer-openings at or near its top, a wind-conduit communicating with the twyer-open-

ings, and a deflector in said wind-conduit, substantially as described.

4. In an underfeed stoker, the combination of a retort or magazine provided with a series of twyer-openings at or near its top, a wind-conduit communicating with the twyer-openings, and an adjustable deflector in said wind-conduit, substantially as described.

5. In an underfeed stoker, the combination 10 of a retort or magazine provided with a series of twyer-openings at or near its top, a jacket entirely surrounding said magazine to form a wind-box and communicating with the twyer-openings, a wind-trunk communicating with said wind-box, and a deflector, substantially as described.

6. In an underfeed stoker, the combination 20 of a retort or magazine, a jacket surrounding the same to form a wind-box, provided with openings, and a series of twyer-blocks seated thereon and provided with openings communicating with the openings in the wind-box, substantially as described.

7. In an underfeed stoker, a fuel-magazine 25 having one or more sets of lugs arranged transversely around the same with the metal of the body of the magazine between the lugs made thinner to afford a line of fracture, and clamping-bolts uniting said lugs substantially as described.

8. In an underfeed stoker, the combination 30 of a magazine having a conduit leading into the same, twyer-blocks arranged at the top of said magazine and communicating with said conduit, and an air-trunk partly surrounding said conduit and communicating with said magazine, substantially as described.

9. In an underfeed stoker, the combination 35 of a magazine, a jacket to form an air-chamber around said magazine, twyer-blocks communicating with said air-chamber and bolts adapted to engage in recessed openings in the abutting ends of said twyer-blocks, substantially as described.

10. In an underfeed stoker, the combination 40 of a magazine, a laterally-projecting flange therefrom, an air-chamber surrounding said magazine, twyer-blocks mounted thereon, and bolts extending through said flange and having heads adapted to engage oppositely-arranged recessed openings in adjacent ends of said twyer-blocks, substantially as described.

11. In an underfeed stoker, the combination 45 of an air-chamber a fuel-magazine, an air-trunk, and a fuel-conduit, said air-chamber surrounding said magazine and said air-trunk partly surrounding said conduit, of a pocket in said conduit and an air-pipe leading from said air-trunk to said pocket, substantially as described.

12. In an underfeed stoker, the combination 50 of a fuel-magazine having an air-chamber completely surrounding the same, a laterally-projecting flange connecting the tops

of both and adapted to form a top for said air-chamber with openings in said flange having tapered sides, and twyer-blocks having correspondingly-tapered flanges to fit in said openings, said twyer-blocks being formed with openings on the faces thereof, and adapted to fit together to form a continuous extension for the top of said magazine, substantially as described.

13. In an underfeed stoker, the ball-bearing mechanism for the screw conveyer consisting of the recessed plate *c*, annularly-grooved rings *d* in said recess, balls *e* in said grooves between the rings, and the shouldered sleeve *g* fast on the conveyer-shaft and having in said plate *c* substantially as described.

14. In the motor mechanism of an underfeed stoker, the combination of a screw conveyer, a ratchet for operating the same, a vibrating dog-carrier with means for vibrating the same, and a double-nosed dog having two pivotal bearings connected by a slot pivoted to said carrier and adapted to be shifted so that either nose may engage the ratchet to control the direction of revolution of the screw conveyer, substantially as described.

15. In the motor mechanism of an underfeed stoker, the combination of a screw conveyer, a ratchet for operating the same, a vibrating dog-carrier with means for vibrating the same, a double-nosed dog having two pivotal bearings connected by a slot pivoted to said carrier and adapted to be shifted so that either nose may engage the ratchet to control the direction of revolution of the screw conveyer, and a stop-dog for said ratchet adapted to be shifted to either side thereof substantially as described.

16. In the motor mechanism of an underfeed stoker, the combination of a screw conveyer, a ratchet for operating the same, a vibrating dog-carrier with means for vibrating the same, a double-nosed dog pivoted to said carrier and adapted to be shifted so that either nose may engage the ratchet to control the direction of revolution of the screw conveyer, and a two-part stop-dog, of unequal lengths, for said ratchet adapted to be shifted to either side thereof, substantially as described.

17. In the motor mechanism of an underfeed stoker, the combination of a screw conveyer, mechanism for actuating the same, a casing for said mechanism provided with an opening in front, and an eccentrically-set indicator revolving with the conveyer-shaft adjacent to the opening in the casing, whereby the attendant can observe the rotation of the screw conveyer, substantially as described.

18. In the motor mechanism of an underfeed stoker, the combination of the screw-conveyer ratchet *j* and its vibrating dog-carrier *k* of the double-nosed dog *n* having two pivotal bearings *q r* connected by a slot *s*, substantially as described.

19. In an underfeed stoker, the combination of a fuel-magazine, a fuel-conduit lead-

ing therefrom, a fuel-hopper for said conduit, and a screw conveyer in said conduit and magazine and journaled through the front wall of said conduit and having a removable bearing-plate within the conduit at its rear end, substantially as described.

20. In an underfeed stoker a fuel-magazine having one or more portions of less thick-

ness than the body thereof combined with a bridge or bridges spanning the same, whereby the parts are held together in case of fracture.
